Patented July 22, 1913.

UNITED STATES PATENT OFFICE.

CHARLES D. ROBERTS, OF MONROE, NORTH CAROLINA.

UMBRELLA.

1,068,275.

Specification of Letters Patent. Patented July 22, 1913.

Application filed July 2, 1912. Serial No. 707,816.

To all whom it may concern:

Be it known that I, CHARLES D. ROBERTS, a citizen of the United States, residing at Monroe, in the county of Union and State 5 of North Carolina, have invented new and useful Improvements in Umbrellas, of which the following is a specification.

This invention relates to folding umbrellas and the object of the invention is to 10 provide a cheaply constructed, durable, and efficient structure of this type in which the rib may be folded so that the device may be packed in a small compass.

A further object of the invention is the 15 provision of novel means for locking the telescoped parts of the handle or staff in extended or telescoped position.

Further objects of this invention will appear as the following specific description is 20 read in connection with the accompanying drawing, which forms a part of this application, and in which:—

Figure 1 is a side elevation of the staff showing a single rib runner and spreader 25 thereon. Fig. 2 is a detail longitudinal view through the staff. Fig. 3 is a detail longitudinal sectional view through the rib on an enlarged scale. Fig. 4 is a perspective view of the umbrella in folded position.

In the specific embodiment of the invention, as illustrated herein, the staff is constructed of two parts 1 and 2, the latter telescoped within the former and being provided with a split end 3 in which a wedge 4 30 is adapted to operate. This wedge is carried by a rod 5 which slides in the portion 2 and is provided with a headed button 6 operated in the bayonet slot 7, by which means the wedge may be held in operative position 35 with the split end spread in the section 1.

It will therefore be understood how the section 2 may be held rigidly to section 1 in either extended or telescoped position.

The section 1 has secured thereto the ordinary rib pivoting member 8 upon which the ribs 9 are pivoted. The ribs 9 are each formed in two sections 10 and 11, the former having the offset end 12 which carries a clamp or guide 13 in which the lower or 45 outer section 11 is adapted to slide, the off-

set end producing a shoulder, as shown at 14, to hold the section 11 against movement, as will be hereinafter described. Secured to the inner terminal of the section 11 is a clamp or guide member 15 to the lower end 55 of which is pivoted the spreader member 16. This spreader is in turn connected to the runner 17 and carries adjacent the end which is pivoted to the clamp, a heel 18 which is adapted to bear upon the under side 60 of the offset end 12 so as to hold the end of the section 11 depressed into engagement with the shoulder 14. When the runner is moved downwardly over the staff, this heel 18 will be moved out of engagement with 65 the offset portion 12 and the section 11 will be telescoped on to the section 10.

What is claimed is:—

1. In a folding umbrella, a staff, a two-part rib pivoted thereto, one of said parts 70 having an offset end, guide members carried by the offset end and the opposite section or part, and adapted to slidably receive the other part, said offset end forming a shoulder, a runner, a stretcher member pivoted 75 to the runner and to the guide member on the opposite part, and means carried by the stretcher for drawing the end of said opposite part behind the shoulder.

2. In a folding umbrella, a staff, a two-part rib pivoted thereto, the inner part having an offset outer terminal adapted to form a shoulder against which the outer section or part is adapted to abut, a guiding member carried by the offset terminal of the inner part and adapted to receive the outer part, a guiding member carried by the outer part and adapted to receive the inner part and a spreader member pivoted to the last named guide member and having a 80 cam to engage the offset end of the inner part whereby the inner terminal of the outer part will be forced into engagement with the shoulder.

In testimony whereof I affix my signature 95 in presence of two witnesses.

CHARLES D. ROBERTS.
